UNITED STATES PATENT OFFICE.

WELFORD G. EDWARDS AND CLAYTON EDWARDS, OF PLAINVIEW, MINNESOTA.

MILLING AND KEYWAY-CUTTING ATTACHMENT FOR LATHES.

1,405,909.

Specification of Letters Patent.

Patented Feb. 7, 1922.

Application filed June 25, 1920. Serial No. 391,758.

To all whom it may concern:

Be it known that we, WELFORD G. EDWARDS and CLAYTON EDWARDS, citizens of the United States, residing at Plainview, 5 in the county of Wabasha and State of Minnesota, have invented certain new and useful Improvements in Milling and Keyway-Cutting Attachments for Lathes; and we do hereby declare the following to be a full, 10 clear, and exact description of the invention, such as will enable others skilled in the art to which it appertains to make and use the same.

Our invention has for its object to provide 15 an extremely simple and highly efficient milling and key-way cutting attachment for lathes, and to this end, it consists of the novel devices and combinations of devices hereinafter described and defined in the 20 claims.

In the accompanying drawings, which illustrate the invention, like characters indicate like parts throughout the several views.

Referring to the drawings:

25 Figure 1 is a plan view of the attachment and a portion of a lathe, with some parts broken away;

Fig. 2 is a view principally in side elevation, with some parts shown in section and 30 other parts diagrammatically illustrated by means of broken lines; and

Fig. 3 is a front elevation of the attachment removed from the lathe.

Fig. 4 is a vertical section on a somewhat 35 enlarged scale taken on the line 4-4 of Fig. 1.

Of the parts of the lathe illustrated, it is important to note the bed 4, carriage-ways 5 having T-shaped channels 6, milling tool 40 7, and tool post 8. The attachment includes a flat base plate 9 adapted to rest transversely on the ways 5 and provided with a longitudinally extended and centrally located slot 10, through which extends a pair 45 of nut-equipped bolts 11. The bolts 11 have

T-heads adapted to be secured in the channels 6 for detachably securing the attachment to the lathe carriage. Obviously, the slot 10 permits the bolts 11 to be set different 50 distances apart in order that the attachment may be applied to lathes of different widths.

Secured to the inner end of the base plate 9 is a wide hinge lug 12, and the forward end of said base plate is bifurcated to afford 55 a pair of prongs 13, to the upper faces of which is secured a pair of bearing blocks

14. A vertically swinging nut block 15 is mounted between the prongs 13, and provided with a pair of trunnions 16 journaled in seats formed in said prongs and the bearing blocks 14.

A pair of track rails 17 have their rear ends arranged to receive therebetween the hinge lug 12, and are pivoted thereto by a hinge bolt 18 for vertical swinging movement. 60 These track rails 17 are rigidly but adjustably connected by cross-ties 19 having one of their ends rigidly secured to one of the track rails 17 and their other ends are provided with screw threads and inserted through bores in the other of said track rails. Opposing nuts 20, on the screw-threaded ends of the cross-ties 19, rigidly hold the respective track rail 17 therebetween with freedom for adjustment toward 65 and from the other of said track rails.

The free ends of the track rails 17 are raised and lowered by a vertical feed screw 21 mounted in the nut block 15 and having its upper ends swiveled at 22 to the front 70 cross-tie 19. On the lower end of the feed screw 21 is a hand piece 23, by which said feed screw may be operated to raise and lower the free ends of the track rails 17. Mounted on the track rails 17 is a work-holding carriage 24, having on its longitudinal edges flanges 25 slidably mounted in longitudinally extended grooves 26 formed in the inner faces of the track rails 17 above the cross-ties 19. This carriage 24 is further guided and supported on the track rails 17 by a pair of horizontally spaced plates 27 rigidly secured to the upper face of the carriage and slidably supported on the upper edges of the track rails 17. Obviously, 80 by releasing the outer nuts 20, the track rails 17 may be pulled apart to receive therebetween the carriage 24 and then set to cause the flanges 25 to enter the longitudinal groove 26 in the track rail for free sliding movement.

Resting on the carriage 24, between the plates 27, is a work support or table 28, which, as shown, extends the full length of said carriage and is provided in its upper 85 face with a longitudinally extended and centrally located V-shaped groove 29, to receive and hold a piece of work, such as a shaft Z, as best shown in Fig. 3. To clamp and hold the work in the groove 29, there is provided a clamp, in the form of a pair of upright nut-equipped studs 30, and a clamp- 90 100 105 110

ing bar 31 vertically movable on said studs under the nuts thereof. These studs 30 are anchored, at their lower ends, in the carriage 24.

5. To operate the work-holding carriage 24, on the track rails 17, there is secured, in the customary slot in the tool post 8, a rectangular metal bar 32 having on one of its ends a trunnion 33. One end of a link 34 is pivoted to the trunnion 33 and its other end is pivoted to a trunnion 35 on one of the carriage plates 27. With the carriage 24 thus connected to the tool post 8, the same may be moved by the cross feed of the lathe carriage to feed the work Z to the milling tool 7.

The above described attachment may be very quickly applied to a lathe carriage or removed therefrom without disturbing any of the parts of the lathe. By the use of the improved attachment, there is no waste of time in lining up the work and the depth of the cut in the work may be regulated by the feed screw 21. This attachment may be used in cutting all kinds of key-ways, including 20 the Woodruff, squares and surfacing, and without any chatter or trembling, regardless of depth of cut or feed. When the track rails 17 are in horizontal position, the key-way can be cut with its bottom parallel to 25 the axis of the shaft. A key-way can also be so cut when the tracks are inclined by 30 suitably turning the feed screw 21.

What we claim is:

1. An attachment of the kind described 35 comprising a base, a track having one of its ends hinged to the base, an adjusting screw for raising and lowering the other end of the track, a carriage arranged to travel on the track, a work-holding device on the 40 carriage, and means for operating the carriage.

2. An attachment of the kind described comprising a base, a track having one of its 45 ends hinged to the base, a feed screw swiveled in the other end of the track, a nut block on the feed screw secured to the base for swinging movement, a carriage arranged to travel on the track, a work-hold-

ing device on the carriage, and means for operating the carriage.

3. An attachment of the kind described comprising a base, a pair of track rails hinged at one of their ends to the base, cross-ties adjustably connecting the track rails, said track rails having on their inner faces 55 longitudinally extended grooves, means for raising and lowering the other ends of the track rails, a carriage slidably mounted in said grooves, a work-holding device on the carriage, and means for operating the carriage. 60

4. An attachment of the kind described comprising a base, a vertically adjustable track mounted on the base, a carriage arranged to travel on the track and having 65 a longitudinally extended groove, a pair of nut-equipped studs located, one on each side of said groove and anchored to the carriage, a clamping bar on the studs, and means for operating the carriage. 70

5. The combination with a lathe, of a base secured to the lathe, an adjustable track secured to the base, a carriage arranged to travel on the track, and means for operating the carriage from a movable part of the 75 lathe.

6. The combination with a lathe, of a base detachably secured to the lathe carriage, an adjustable track secured to the base, a carriage arranged to travel on the track, and 80 means for operating the carriage from the tool post of the lathe.

7. The combination with a lathe, of a base detachably secured to the lathe carriage, an adjustable track secured to the base, a carriage arranged to travel on the track, and a link having one of its ends pivoted to the last noted carriage and having its other end pivoted to a part carried by the tool post. 85

In testimony whereof we affix our signatures in presence of two witnesses.

WELFORD G. EDWARDS.
CLAYTON EDWARDS.
